UNITED STATES PATENT OFFICE.

CHARLES P. BOSSERT, OF MILWAUKEE, WISCONSIN.

DISPENSING-VALVE.

1,374,980.

Specification of Letters Patent. Patented Apr. 19, 1921.

Application filed December 16, 1919. Serial No. 345,418.

To all whom it may concern:

Be it known that I, CHARLES P. BOSSERT, a citizen of the United States, and resident of Milwaukee, in the county of Milwaukee, and State of Wisconsin, have invented certain new and useful Improvements in Dispensing-Valves; and I do hereby declare that the following is a full, clear, and exact description thereof.

10 My invention relates to new and useful improvements in dispensing valves, more particularly of that type adapted to discharge a limited quantity of liquid upon each actuation of the operating member of the valve, such valves being adapted for use in dispensing soap or the like.

It is in general the object of my invention to simplify and otherwise improve the construction and to increase the efficiency of 20 valves of this character, to the end of providing a compact valve which is positive in operation to eject a certain limited quantity of liquid upon each actuation of the operating member of the valve, and to prevent 25 leakage through the valve after a certain amount of liquid has been discharged.

Such valves are usually provided with a measuring chamber in which is disposed a plunger to procure ejection of the limited 30 amount of liquid, the valve member being adapted to operate by reason of the velocity flow of liquid to either close off flow of liquid from the reservoir into the valve, or from the measuring chamber through the 35 discharge port of the valve.

It is a further object of my invention to provide an arrangement wherein the plunger, upon movement in either direction, imparts an initial movement to the valve 40 member so as to reduce the liability of sticking of the valve member.

With the above and other objects and advantages in view, which will be apparent as the description proceeds, my invention 45 resides in the novel features of construction, combination and arrangement of parts which will be hereinafter more particularly described and defined by the appended claims.

50 In the accompanying drawings:

Figure 1 is a longitudinal sectional view through a soap dispensing valve constructed in accordance with my invention.

Fig. 2 is an end view of the valve member.

Fig. 3 is a transverse sectional view through the valve member on a plane indicated by the line 3—3 of Fig. 1.

Fig. 4 is a similar view taken on a plane indicated by the line 4—4 of Fig. 1.

Fig. 5 is a similar view on a plane indicated by the line 5—5 of Fig. 1.

Fig. 6 is an inner end view of the valve.

Referring now more particularly to the accompanying drawing, my improved valve structure comprises an elongated cylindrical casing 10 divided in its intermediate portion by a relatively wide partition 11 to form a measuring chamber A at its outer portion, and a valve chamber B at its inner portion, the partition being provided with a central aperture to permit communication between the chambers. The outlet port 12 of the valve extends obliquely through the bottom of the wall of the main casing 10 at 75 its intermediate portion and opens at the inner side of the partition 11. A plug 13 is threaded in the valve chamber end of the casing and is provided with a plurality of longitudinal inlet ports 14 and with a 80 nipple portion 15 whereby the valve may be secured to any suitable reservoir or other source of supply. A stem 16 is slidable axially in the plug 15 and is extended through the chambers of the casing and the partition 11, said stem being threaded into the inner end of a plunger 17 which is slidable in the measuring chamber end of the casing. A spring 18 is coiled on the stem within the measuring chamber A and bears against 90 the plunger and against the partition 11, outward movement of the plunger being limited by a head 19 on the inner end of the stem 16, said head being adapted to engage against the plug 13 and incidentally 95 to close the inlet passages 14 of the plug. A sleeve 20 is slidably mounted on the stem 16 within the valve chamber B and is provided at one end with a radial flange 21 adapted to engage against the plug 13 and 100 close the inlet ports 14, said sleeve being also provided with a series of longitudinally extending radial ribs 22 which project beyond the other end of the sleeve and carry a disk 23 adapted to seat against the adjacent face of the partition 11 and close the

105

outlet port 12, said disk being provided with a central aperture of such diameter as not to interfere with free passage of liquid between the chambers.

5 Entering now into the operation of my improved valve structure, it will be seen that the plunger 17 which constitutes the operating member of my valve and is therefore provided with a suitable head 24 at its outer 10 end, is normally disposed outwardly and the headed end 19 of the stem 16 is urged against the plug 13 to provide a positive closure preventing passage of liquid from the reservoir. The disk 23 is also engaged against the partition 11, thus closing the discharge port 12 of the valve and a certain amount of liquid is contained within the measuring chamber A and the valve chamber B. To actuate the valve, the plunger 17 is moved inwardly and 15 in this inward movement of the plunger the valve member will be carried on the stem 16 thus uncovering the discharge port 12 and seating the flange 21 against the plug 13 to close the inlet ports 14. The amount of liquid displaced by the plunger 17 in its inward movement is thus forcibly ejected from the valve, and when such ejection has occurred, the valve member will slide on the stem to close the discharge port 12 by reason of flow 20 of liquid from the reservoir. This movement is however more thoroughly effected when the plunger 17 is normally released after being moved to its inward limit of movement, thus causing the plunger to move 25 outwardly under the action of the spring. As the plunger moves outwardly, it will draw a successive charge of liquid into the measuring chamber, the flow of fluid in either direction through the valve chamber 30 serving to move the valve to its selective closing position by impinging against the flange and disk portions of the valve member.

I have thus provided an exceedingly simple and efficient dispensing device in which, 45 upon movement of the plunger in either direction the flow of liquid to and from the measuring chamber effectively imparts the desired moving impulse to the valve member which is reciprocably mounted on the stem 50 of the plunger. It is noted that in the normal closing position of the valve, a double seal is afforded against leakage through the valve, by the disk 23 and stem head 19.

While I have shown and described a preferred embodiment of my invention, it will 55 be appreciated that various changes and modifications of structure may be employed to meet differing conditions of use and manufacture without departing in any manner 60 from the spirit of my invention.

What is claimed is:

1. A valve structure of the class described comprising a storage chamber, a valve chamber in communication with the storage chamber, a valve member reciprocable in the valve 65

chamber, inlet and outlet ports for the valve chamber, a plunger having a stem slidable in the measuring chamber, said valve being slidably mounted on said stem and operable by the flow of liquid upon reciprocation of 70 the plunger to open and close said ports successively.

2. A valve structure of the class described comprising a measuring chamber, a valve chamber in communication with the storage chamber, a valve member reciprocable in the valve chamber, inlet and outlet ports for the valve chamber, a plunger slidable in the measuring chamber, and a stem secured to the plunger and slidably engaged with the 75 valve member.

3. A valve structure of the class described comprising a measuring chamber, a valve chamber in communication therewith, a plunger slidable in the measuring chamber, a stem extending from the plunger through said chambers, a valve sleeve slidable on the stem within the valve chamber, inlet and outlet ports for said valve chamber, and portions carried by said sleeve for selectively 80 closing said ports.

4. A valve of the class described comprising a measuring chamber, a valve chamber in communication therewith, inlet and outlet ports for the valve chamber, a plunger 95 slidable in the measuring chamber, means resiliently urging said plunger outwardly, a stem extending from said plunger through the chambers, a head on said stem adapted to close the inlet port of the valve chamber 100 in outward position of the plunger, and a valve member movable in the valve chamber to selectively close said ports.

5. A valve of the class described comprising a measuring chamber, a valve chamber 105 in communication therewith, inlet and outlet ports for the valve chamber, a plunger slidable in the measuring chamber, means resiliently urging said plunger outwardly, a stem extending from said plunger 110 through the chambers, a head on said stem adapted to close the inlet port of the valve chamber in inward position of the plunger, and a valve member slidable on the stem and adapted to selectively close said ports. 115

6. A valve of the class described comprising an elongated casing provided with an intermediate partition apertured to afford communication between the consequent measuring and valve chambers formed thereby, a closure for the valve chamber end of the casing, a plunger slidable in the measuring chamber end of the casing, inlet and outlet ports for the valve chamber, a valve member in the valve chamber movable to 120 selectively close said ports, and a stem extending from the plunger and slidably engaged with the valve member.

7. A valve of the class described comprising an elongated casing provided with an 125

intermediate partition apertured to afford communication between consequent measuring and valve chambers formed thereby, a closure for the valve chamber end of the 5 casing, a plunger slidable in the measuring chamber end of the casing, an inlet port for the valve chamber, an outlet port for the valve chamber extending from the ad-

jacent side of the partition obliquely through the wall of the casing, and valve means controlling flow of liquid through the ports. 10

In testimony that I claim the foregoing I have hereunto set my hand at Milwaukee, in the county of Milwaukee and State of Wisconsin.

CHARLES P. BOSSERT.
